CLAIM

The ornamental design for a laser gunsight system for a firearm trigger guard, as shown and described.

DESCRIPTION

FIG. 1 is a front perspective view of a laser gunsight system for a firearm handgrip showing my (our) new design;

FIG. 2 is a top view thereof;

FIG. 3 is a right side view thereof;

FIG. 4 is a bottom view thereof;

FIG. 5 is a front view thereof;

FIG. 6 is a left side view thereof; and,

FIG. 7 is a front fragmentary view thereof.

The broken lines form no part of the claimed design.
